YARN FEED MECHANISM FOR KNITTING MACHINES

Michael Zimic, Lake Success, and Anton Miskovsky, Deer Park, N. Y.; said Miskovsky assignor to said Zimic

Application December 28, 1949, Serial No. 135,394

2 Claims. (Cl. 66—126)

1

The present invention relates to means for feeding yarn in knitting machines, and more particularly, to novel means for controlling the position of a yarn guide or feeder and moving the yarn feeder and its carrying means over a predetermined range of movement to provide special knitting operations or special knitting sequences.

In accordance with the invention, a yarn carrier is provided with a movable yarn guide comprising or being joined to a suitable mounting arm having yarn feeding means for bringing a strand of yarn from a supply source to the yarn guide. The carrier is movable along a stationary trackway, or the like, usually provided in a knitting machine of the type generally known as a links and links machine. Movement of the guide with respect to the carrier, as well as the movement of the carrier on the trackway, or its equivalent, is coordinated automatically by means also movable on the trackway. The last named means preferably resembles the carrier and acts through a lost motion link member of special design. Also, in accordance with the invention, the yarn selecting mechanism on the traveling carriage of a links and links knitting machine cooperates substantially without modification with the yarn feeding mechanism of this invention to move the guide with respect to the carrier, and to move the carrier to provide for feeding yarn to the knitting devices, such as latch type needles in the knitting bed or beds of the machine.

The principal object of the present invention is to provide novel means for controlling the yarn guide in a knitting machine.

Another object is to provide a novel yarn guide which is movable with respect to its carrier. A feature or object of the invention which is closely related to the object just stated, is to provide novel means for causing movement of the movable yarn guide with respect to its carrier.

A further object is to provide a novel carrier mechanism for a yarn guide together with an additional instrumentality in the form of a second carrier for controlling the position of the yarn guide with respect to the first carrier.

Other objects and advantages of the present invention will, of course, become apparent and immediately suggest themselves to those skilled in the art to which the invention is directed from a reading of the following specification in connection with the accompanying drawings, in which:

Fig. 1 is a view in elevation of a portion of the

trackway for the yarn carrying mechanism of a knitting machine having an illustrative embodiment of the yarn carrying control mechanism of this invention thereon;

5 Fig. 2 is a section taken on line 2—2 of Fig. 1;

Fig. 3 is a view in plan of the mechanism of Fig. 1;

Fig. 4 is a fragmentary showing of the mechanism of Fig. 1 as viewed from the rear;

Fig. 5 is a section taken on line 5—5 of Fig. 4; and

Figs. 6 to 8 are views similar to Fig. 1 showing successive stages in operation of the illustrative form of mechanism.

15 The yarn guide together with the mechanism for controlling and moving it, embodying this invention, is to be employed in a knitting machine of the type, for example, known as the links and links machine which includes a needle bed or beds 7 and 8, and a carriage (not shown), which reciprocates over these beds. The carriage includes a lock or cam mechanism for actuating the needles 9 in the bed or beds in sequence to form stitches in the yarn which is fed to the

20 needles along with and under control of the carriage. Only a fragment 10 of the carriage appears in the drawing. Inasmuch as knitting machines of this general type are by now well known, the mechanism of the knitting machine

25 has been omitted for the sake of simplicity. The knitting machine usually includes one or more trackway bars 12, one of which appears in the drawing. These trackway bars are supported in any suitable manner so that they lie above the

30 needle beds 7 and 8 of the knitting machine. In the illustrative example only one trackway bar 12 is shown. However, where a plurality of these bars are employed, they are spaced horizontally and the yarn guides are offset laterally from their carriers to insure that the yarn is fed to the needles in their active position. The trackway bar 12, as shown in Fig. 2, has two projections 14 and 16 which extend longitudinally of the bar. Reference character 18 designates, in its

35 entirety, the carrier for the yarn guide 19 of the invention. The carrier 18 is provided with a recess 21, the top portion 22 of which is of a shape in outline to fit over a dovetail portion of a trackway bar such as the portion 14. A member 24 is

40 slidably mounted on the body of the carrier 18 and it is provided with a surface 26 which presses upwardly against the bottom of the projection 14. A flat spring 28 secured to the body of the carrier 18 presses the member 24 upwardly so

45 that the carrier 18, while it is slidable on the

projection 14, is frictionally held in position unless it is moved positively by a yarn selecting instrumentality, a part of which, namely, the finger 31, appears on the drawing. It will be understood that the vertical position of the finger 31 is controllable by suitable mechanism associated with the carriage so that it may be raised or lowered to provide for engagement with the carrier 18 or an additional sliding member 33 which resembles, somewhat, the carrier 18.

The yarn guide 19 is carried by a mounting 34 which is in the form of an offset arm. The degree of offset will be determined by the placement of the trackway bar laterally with respect to the active position of the needles. This mounting is pivoted at 36 on the carrier 18. Its range of movement is defined by inclined surfaces 41 and 42, and vertical surfaces 44 and 45. These surfaces determine the range of swinging movement of the mounting 34 on the carrier 18. A spring 49 urges mounting 34 in a clock-wise direction as viewed on the drawing.

The additional sliding member 33, referred to above, is provided with a recess 48 having a sloping top surface 49'. Like the carrier 18 it is provided with a member 52 slidably mounted in its body portion and having a top sloping edge 54. A spring 56 urges the member 52 upwardly so that the sliding member 33 will be frictionally held in position on the elongated dovetail projection 14.

The sliding member 33 has a projecting post 58 secured to it which is grooved as indicated at 59 to receive the slot 62 in a link member 64. One side of the slot 62 is interrupted at points 66 and 67 so that the link 64 may be readily engaged with and disengaged from the groove 59 on the projection 58. The point 67 is adjustable since it is at the end of a slider 70 which can be clamped on the bar 64 at a selected point. The slot 62 continues between the bar 64 and the arm on the slider 70. The link member 64 is pivotally connected as indicated at 68 to the extending end 69 of the mounting 34 for the yarn guide 19.

In the position of the part illustrated by Fig. 1 of the drawing, the sliding member 33 is positioned to the left of its range of travel on the dovetail portion 14 of the trackway bar 12. The spring 56 acting on the sliding member 52 maintains the entire sliding member 33 in position because of its frictional engagement with the trackway bar extension. The carrier 18 is positioned on the dovetail extension 14, as shown, and it is retained in this position also by frictional engagement caused by pressure of the sliding member 24 which is acted upon by the spring 28. The yarn guide 19 is, therefore, in an elevated position inasmuch as the mounting 34 is tilted about its pivot 36. The carriage (fragmentarily shown) of the knitting machine is assumed to be at the left hand end of its range of travel and as it moves toward the right, as viewed on the drawing, the finger 31, or an equivalent member, on the carriage engages the edge 71 of an upwardly projecting portion 72 of the sliding member 33. This member 33 is propelled to the right until the finger 31 engages the upwardly sloping cam surface 74 which is formed on a finger 75. This finger 75 is pivoted on the extension 78 of a block 79 which is grooved as indicated at 82 so that it may be clamped to the dovetail 14 by means of a thumb screw or machine bolt 84. As seen in Fig. 1, the finger 75 is urged inwardly toward the bar 12 by means of a flat spring 86. As stated previously, when

the finger 31 encounters the cam surface 74, it rides upwardly so that it releases the edge 71 of the projection 72. It will be noted that the member 58 which projects from the sliding member 33 has been moved a distance substantially equal to the total length of the slot 62 in the link 64. The first part of the movement of the sliding member 33, prior to its release, permits the link 64 to move to the right thereby lowering the guide 19 to its active position. At this stage, the parts are in the position of Fig. 6 of the drawing.

As the finger 31 proceeds toward the right, it engages the edge 89 of the projection 91 on the carrier 18, as shown in Fig. 7. The carrier 18 is thereby moved to the right, the slot 62 permitting this movement without causing the mounting 34 to pivot with respect to the carrier 18 until the finger encounters the cam surface 93 of a second cam raising finger 94. At this time the parts are in the position shown by Fig. 8 of the drawing.

From this point the carriage and the associated finger 31 move to the right to complete such other knitting operation as provides the field or background for the stitches supplied by the yarn guide 19 until it reaches the extreme limit of travel to the right, which may, in some instances, be beyond the right hand edge of the fabric which is being knitted.

30 The carriage next begins its return stroke and when the finger 31 encounters the finger 94 this finger moves aside on its pivot 98. Prior to this, however, 31 has engaged the edge 101 of the projection 91 to move the carrier 18 until the finger 35 encounters the sloping edge 104 of a finger 106. The finger 106 is carried by a member 116 which is similar to the member 79. The carrier 18 comes to rest substantially in the position shown by Fig. 7 and as the finger 31 proceeds to the left, 40 it engages the right edge 108 of the projection 72 to move the sliding member 33 back to its position originally occupied, shown in Fig. 1. When the sliding member 33 has reached this position, the finger 31 encounters the sloping end 112 of the finger 114. The finger 114 is carried by a member 118 which is similar to the member 79. The carriage then proceeds to the left hand edge of the machine. This cycle of operations is repeated in operation of the knitting machine in accordance with this invention.

In accordance with one possible method of operation of a knitting machine equipped with the yarn guide of this invention, the field or background of the fabric to be produced is knitted from a continuous yarn in any usual and known manner. This yarn may be held back by selected needles (not shown as not directly concerned in an understanding of this invention) while the yarn fed by the guide 19 is laid in on another selected set of needles (also not shown). The movement of these needles is controlled by the carriage travel and the proper set up of the jacks (not shown) which position the needles under control of the carriage lock or cam mechanism.

When the fabric pattern calls for an inset or a special section after the plain section or field has been knitted, the pins on the carriage will be projected to pick up the yarn carrier 18 for the proper number of rounds. The yarn for the field or background continues to move with each round of the carriage but is held back out of the way while the small section is laid in by the guide 19 on the needles which knit the inset or small section. At the edge of the inset, a common needle may be used to join the yarn for the field

and the inset. The foregoing is given only by way of example as a possible mode of operation of the invention and is not to be interpreted as restrictive.

Having now described the invention, what is claimed is:

1. A yarn feeding mechanism for a knitting machine comprising a block member having a recess therein to be received on the trackway of a knitting machine, a pivot on said block member, an arm having a yarn guide, said arm being pivotally mounted on said pivot, an extension on said arm, a link pivoted to said extension, a second block having a recess to be received on the trackway of a knitting machine, a projection on said second block, an elongated slot in said link engaged with said projection to provide a lost motion connection between said link and said projection, a tension spring pivotally connected between said link and said first block member whereby said arm is biased for rotation in one direction, and means comprising a friction shoe and a spring on both said first named block and said second named block for frictionally positioning said blocks on a trackway of a knitting machine.

2. A yarn feeding mechanism for a knitting machine comprising a block member having a recess therein to be received on the trackway of a knitting machine, a pivot on said block member, an arm having a yarn guide, said arm being pivot-

ally mounted on said pivot, an extension on said arm, a link pivoted to said extension, a second block having a recess to be received on the trackway of a knitting machine, a projection on said second block, an elongated slot of adjustable length in said link engaged with said projection to provide a lost motion connection between said link and said projection, a tension spring pivotally connected between said link and said first block member whereby said arm is biased for rotation in one direction.
